RECTIFYING MEANS

Charles Spaeth and Herbert Peary, Chicago, Ill.,
assignors, by mesne assignments, to Old Colony
Trust Company, a corporation of Massachusetts

Application May 4, 1927. Serial No. 188,730

3 Claims. (Cl. 250—27.5)

Our invention relates to rectifying means and more particularly to a point to plate rectifier and has for its object the provision of a rectifier of this character which will be easily assembled and when assembled will be strong and rugged so as to be capable of standing up under severe usage without danger of the parts becoming disaligned or broken by jar due to careless handling of the device.

10 It is another purpose of this invention to provide a novel means for supporting the electrodes in the rectifier tube and properly spacing them.

Other objects and advantages of the invention will appear as the description proceeds when taken in connection with the accompanying drawing. However, we wish it to be distinctly understood that we do not intend to limit ourselves to the exact details shown and described, but that we intend to avail ourselves to all such 20 modifications as occur to one skilled in this art and as fall within the scope of the claims.

In the drawing:

The figure is a sectional view of a full wave rectifier embodying the invention.

25 Referring now in detail to the drawing, the numeral 5 indicates the usual evacuated tube housing the rectifier. This tube is preferably evacuated to a very high state of rarefaction and is then filled with a suitable gas such as one of the noble gases such as helium or neon. The tube is provided with the usual base 6 and in the form shown in the figure has four terminals 7, 8, 9, and 10 for connection to the external circuits in a manner which will be presently explained. The tube is provided with the inwardly 30 projecting stem or press 11 and extending upwardly from this press with the lower ends embedded therein are the metallic rods 12 and 13 forming the point electrodes for the full wave rectifier.

Surrounding the electrodes 12 and 13 and resting upon the upwardly extending portions 14 and 15 of the press 11 are the insulating supporting members 16 and 17 which are provided adjacent the tops thereof with the annular shoulders 18 and 19 forming a seat for the cathode 20 which is substantially cup-like in shape. This electrode is provided in the bottom thereof with a plurality of enlarged openings receiving the inverted cup-like members 21 and 22 which as shown clearly have an annular outwardly extending flange at the bottom thereof resting upon the shoulders 18 and 19.

These cup-like members 21 and 22 are also 55 each provided at the top thereof as at 23 and

24 with an opening considerably larger in diameter than the rods 12 and 13 and through which the said rods project. The members 21 and 22 are firmly held in place by upwardly projecting portions of the insulating members 16 and 17 above the shoulders 18 and 19 which have a tight fit within the members 21 and 22. To fully enclose the point electrodes within the cathode we provide in addition the cap 25 which is secured upon the cup-like member 20 by means of the flanges at 26 and 27 provided on both the members 20 and 25 and the supporting rods 28 and 29 which extend through these flanges and are bent over so as to retain the flanges together, the lower ends of the rods 28 and 29 being molded in the press 11.

In accordance with the well-known operation of point to plate rectifiers, the plate or cathode 20 operates at a temperature below that at which the discharge is dependent upon thermionic emission. The liberation of electrons from the cathode surface occurs, according to the accepted theory of operation of such devices, mainly as a result of the bombardment of that surface by positive ions rather than as a result of thermionic emission as in the usual thermionic type of rectifier. Rectification is accomplished by restricting the active area of the point electrode or anode so that the positive ion bombardment of the ion does not liberate an appreciable number of electrons as compared with the number of electrons so liberated from the more extensive area of the cathode. It has been found by experiment that the introduction of a heated filament in proximity to the point to plate rectifier greatly increases the current rectifying capacity of the rectifying tube and the form of the invention illustrated is provided with such a filament 30 which as shown has one end secured to the cathode and has the other end supported by means of the insulating bushing 32 in electrode 31 and has a conductor 33 extending therefrom downwardly through the press 11 to the terminal 7. It will be noted, however, that the addition of the filament has not changed the fundamental operation of my device. Rectification in the arrangement as shown in the drawing is still dependent on the difference in size between the restricted point electrodes 12 and 13 and the plate or cathode 20. These point electrodes 12 and 13 are connected by means of the conductors 34 and 35 to the terminals 8 and 10 and the cathode is connected by means of the conductor 36 to the terminal 9.

In the operation of the tube a transformer hav- 130

ing the primary 38 and secondary 39 is connected across the usual 110 volt supply of alternating current. In order to supply the filament with current the terminals 7 and 9 which are connected 5 respectively to the filament and the cathode are also connected across the source of alternating current. The opposite ends of the secondary of the transformer are connected to the terminals 8 and 10 and the transformer is preferably such 10 that a relatively high voltage in the neighborhood of 300 volts will be impressed upon the point electrodes 12 and 13. The secondary transformer is tapped midway between its ends and provided with the lead 40 forming one terminal of the output circuit while the terminal 9 is connected by 15 means of the lead 41 to the other side of the output circuit so that upon connecting the primary of the transformer to a source of alternating current, direct current will be supplied continuously 20 to the output circuit by means of the leads 40 and 41 substantially in the manner described in the application of Charles Spaeth on rectifier filed March 4, 1927, under Serial No. 172,701.

The particular advantages obtained by the improved mounting of the electrodes are first, increased strength and rigidity, since the cup-like members 21 and 22 together with the shoulders and upwardly extending reduced portions on the insulating bushings serve to firmly retain the 25 electrodes in properly spaced relation, and second protection of the plate and point electrodes at their areas of support by the bushings. In a rectifier of this character the heaviest current discharge takes place across the shortest gap between the electrodes. By the use of the cup-like 30 members 21 and 22 this discharge is made to take place at the free ends of these members so that it occurs at a distance from the support and the supporting portions are not worn away so as to 35 impair the device structurally by the heavy discharge of current.

From the above description it is thought that the construction and operation of the device will be clear to those skilled in this art and having 40 thus described our invention what we claim and desire to secure by Letters Patent of the United States is:

1. A rectifier comprising a gas filled envelope having a supporting stem therein, spaced metallic rods projecting from said stem insulating bushings surrounding said rods and having annular shoulders thereon adjacent their upper ends, inverted cup-like metallic members having annular flanges resting on said shoulders and projecting above the upper ends of said bushings, said inverted members having openings therethrough through which said rods extend, and a cup-shaped metallic member having spaced openings in the bottom thereof receiving said inverted members, whereby said cup-shaped member engages and is supported by said flanges. 80

2. A rectifier comprising a gas filled envelope having a supporting stem therein, spaced metallic rods projecting from said stem, insulating bushings surrounding said rods and having annular shoulders thereon adjacent their upper ends, inverted cup-like metallic members having annular flanges resting on said shoulders and projecting above the upper ends of said bushings, said inverted members having openings therethrough through which said rods extend, and a cup-shaped metallic member having spaced openings in the bottom thereof receiving said inverted members, whereby said cup-shaped member engages and is supported by said flanges. 85

90

3. A rectifier comprising a gas filled envelope having a supporting stem therein, spaced metallic rods projecting from said stem, insulating bushings surrounding said rods, and having tubular projections at their upper ends closely surrounding said rods, metallic shields surrounding and

projecting above the upper ends of said tubular projections, said shields having annular flanges 100 resting upon said bushings, and a cup shaped metallic member having spaced openings in the bottom thereof receiving said shields, whereby said cup shaped member engages and is supported by said flanges. 105
